UNITED STATES PATENT OFFICE

108,754

DESIGN FOR A SUIT

Jacob A. Silverman, New York, N. Y.

Application January 20, 1938, Serial No. 74,448

Term of patent 3½ years

To all whom it may concern:

Be it known that I, Jacob A. Silverman, a citizen of the United States of America, residing in New York city, in the Borough of Manhattan, county and State of New York, have invented a new, original, and ornamental Design for a Suit, of which the following is a specification, reference being had to the accompanying drawing, forming part thereof, wherein

The characteristic feature of my design resides in the particular arrangement of the quilting on the front and rear jacket and lapel portions, as shown.

I claim:

The ornamental design for a suit, substantially as shown and described.

JACOB A. SILVERMAN.
